IGNITION CONTROL DEVICE

Martin J. Berlyn, Enfield, Conn., and Ernest E. Stansfield, Springfield, Mass., assignors to American Bosch Corporation, Springfield, Mass., a corporation of New York

Application October 16, 1948, Serial No. 54,973

10 Claims. (Cl. 200—31)

1

This invention relates to ignition timers for internal combustion engines and has particular reference to timers of the type which embody a movable circuit breaker plate or supporting means.

An object of the invention is to provide a new and improved supporting means for the circuit breaker assembly which may be moved in angular relation to the cam to provide variation of spark timing in relation to engine crank position.

Another object of the invention is to provide a pivot arrangement for the circuit breaker supporting means or plate which will reduce to a minimum the amount of wobble of the supporting plate resulting from normal wear in said pivot which wobble may cause erratic spark timing and variations in spark timing resulting in rough running of the motor and in extreme cases detonation.

Another object is to provide a pivot arrangement of the type set forth above which shall have a high length-diameter ratio and wherein the use of ball bearings is obviated.

Another object of the invention is to provide an arrangement of the type set forth wherein the pivot for the circuit breaker supporting means is displaced from the cam shaft axis by such an amount that the diameter of its pivot is entirely independent from the diameter of the camshaft and the bearing for the camshaft.

Another object of the invention is to provide a relatively economical yet efficient circuit breaker supporting means.

Other objects and advantages of the invention will be apparent from the following specification taken in connection with the accompanying drawings. The preferred embodiment has been shown by way of illustration only and it will be understood that changes may be made in the details of construction and arrangement of parts without departing from the scope of the invention.

In prior ignition timers of the type which embodied a movable circuit breaker plate or supporting means, it has been customary to employ a bearing which surrounds the camshaft. In such constructions it has been usual to employ ball bearings in an attempt to obviate any wobble or looseness in the bearing which might cause erratic spark timing and variations in spark timing resulting in rough running of the motor and in extreme cases detonation.

As ball bearings are expensive, they have added considerably to the cost of such ignition timing devices and yet where attempts to avoid the use of such ball bearings have been made, the resulting constructions have not been found satisfac-

2

tory in operation because of the inherent looseness or wobble between the parts resulting from normal wear thereof and which resulted in the various difficulties mentioned above. Where a ball bearing was not employed, the length of the pivot about which the circuit breaker supporting plate was pivoted was limited by restrictions on the overall height of the assembly, and with the pivot surrounding the camshaft as was previously employed, a very unfavorable length-diameter ratio for said pivot was obtained.

We have found that by displacing the pivot for the breaker supporting plate away from the cam-shaft axis by an amount making the diameter of the pivot entirely independent from the diameter of the camshaft and its bearing, that it is possible to obtain a satisfactory length-diameter ratio of such pivot and to thereby overcome the inherent difficulty of taking the wobble out of the pivot bearing without the necessity of employing expensive ball bearings. We have found that this can be successfully achieved by positioning the pivot for the breaker supporting plate at such distance from the axis of the camshaft that the distance between the center of the pivot and the center of the camshaft is greater than half the sum of the diameters of the camshaft and pivot bearing but not so great as to affect unduly the amount of contact separation when the interrupter supporting plate is moved through the normal timing range, yet with the camshaft and pivot bearings completely separate.

This construction is aimed primarily at ignition for engines operating on a four stroke cycle and it is, therefore, only necessary to vary the spark timing by an angle measured at the interrupter camshaft center equal to one-half crankshaft spark timing range as measured on the engine crankshaft. Since the timing range normally desired does not exceed thirty crankshaft degrees, then this range does not call for an adjustment of over fifteen degrees in either direction relative to the interrupter camshaft and within this small angle the offset of the pivot for the breaker plate from the center of the breaker camshaft causes no significant change in the breaker point opening. Also, where the follower block is positioned on the midposition of advance and retard, that is, on the line passing through the centers of the breaker support plate pivot center and the camshaft center, that the minimum variations will be obtained.

We have also found that it is possible with such construction to provide a breaker supporting plate made of a minimum amount of material

which allows a maximum amount of movement of the plate and yet may be constructed at a relatively low cost because of the amount of material needed and because of the small bearing required to obtain a satisfactory length-diameter ratio and also that, if desired, a lip on the breaker plate may be provided to engage an undercut internal circumferential guide in the periphery of the housing for further steadyng the plate and relieving the pivot for the plate of some of the bearing load.

Referring to the drawings:

Fig. 1 is a plan view of the ignition distributor with the distributor cap removed and illustrating the invention as applied to a distributor of the engine suction control type;

Fig. 2 is a sectional view taken on line 2—2 of Fig. 1 looking in the direction of the arrows;

Fig. 3 is a sectional view taken on line 3—3 of Fig. 1 looking in the direction of the arrows;

Fig. 4 is a sectional view taken on line 4—4 of Fig. 1 looking in the direction of the arrows; and

Fig. 5 is a plan view of the breaker supporting plate.

Referring more particularly to the drawings wherein similar reference characters designate corresponding parts throughout the several views, the construction shown embodying the invention comprises the usual timer or distributor housing 1 in which is positioned the supporting plate 2 which is provided with the integral peripheral spaced flanges 3 and the screws 4 which extend through aligned openings in the wall of the housing 1 and flanges 3 and secure the plate 2 in position within the housing 1. The flanges 3 may completely surround the plate 2 or may be of such length as is necessary for securing the support 2 to the housing 1 and for providing the guide for the breaker support 5 as hereinafter described.

The timing mechanism employs the usual rotatable cam 6 on camshaft 6a which operates the electrical circuit breaker 7.

The circuit breaker support arm 5 is preferably of substantially U-shape for the reason that such shape will require a minimum amount of material with the resultant reduction in cost of manufacture and at the same time allow a maximum amount of movement for advancing and retarding the spark.

The breaker support arm 5 is provided with the bushing 8 which may comprise a bushing having an enlarged head 9 and a reduced portion extending through an opening in the breaker support 5 with said bushing being secured in position in said opening by brazing or other suitable means. The bushing 8 is adapted to receive the stud 9a which may be secured to the supporting plate 2 by having a portion thereof extending through an opening in the said supporting plate 2 and said portion 10 being riveted over to secure said stud to said plate whereby said stud 9a will form a pivot post for the circuit breaker support 5 about which said support may be adjusted for advancing or retarding the spark as hereinafter described.

On the breaker support arm 5 is mounted the circuit breaker 7 which is mounted for pivotal movement about the pivot 11 and which has the contact 12 adapted to engage the contact 13 on the contact supporting bracket 14 which is secured to the breaker support 5 by the screw 15 and adapted to be adjusted by means of the eccentric stud 16 for adjusting the relative position of the contacts 12 and 13. The spring bracket 17 may also be mounted on the breaker support 5

5 for the securing thereto of one end of the circuit breaker spring 18.

While one form of circuit breaker has been shown by way of illustration, it is pointed out that other types of circuit breakers might be employed such as the so called "pivotless" type, or the contact 13 and circuit breaker 7 might be mounted on a separate bracket wherein the contacts 13 and 12 are positioned in permanent alignment and adapted for adjustment as a unit and said bracket may then be secured on said support 5.

The circuit breaker 7 is provided with the usual cam follower or striking block 19 adapted to engage the cam 6 in the usual manner.

On the breaker support 5 and adjacent the free end thereof is secured the stud 20 to which is secured one end of the coil spring 21 and said spring 21 has its opposite end secured to the stud 22 which is secured to the supporting plate 2 and extends through an enlarged opening 23 adjacent the free end of the breaker support 5. The opening 23 should be of such size as to allow movement of the breaker support 5 for advancing or retarding the spark as hereinafter described.

A suction device is utilized for advancing and retarding the spark. The suction device comprises a flexible diaphragm 24 backed up by a compression coil spring 25 which are mounted in the housing 26 which is connected to the carburetor by the conduit 27. The diaphragm 24 is connected to breaker support 5 by connecting rod 28, one end of which is pivotally connected as at 29 to the support 5 and the other end of which is fixed to the diaphragm 24. The conduit 27 is connected to the carburetor (not shown) in the usual manner.

The breaker support 5 has the lip 30 which engages an undercut, internal circumferential guide in the periphery of the housing 1. For convenience in manufacture this guide 31 has been shown as formed in the peripheral flange 32 on the support 2 although it could be formed directly in the wall of the housing 1 if desired. This arrangement provides a construction wherein the breaker support 5 is further steadied and the pivot 9 relieved of some of the bearing load.

The length of the pivot for the breaker support 5 and form of the stud 9a and bushing 8 is limited by restrictions on the overall height of the assembly and as it is desirable for the pivot to have a high length-diameter ratio so as to reduce to a minimum the amount of wobble of the supporting plate resulting from normal wear in that pivot, it is necessary to employ a pivot of small diameter. If this pivot were concentric with the camshaft, the pivot diameter would necessarily be greater than the camshaft diameter thus giving a very unfavorable length-diameter ratio for this pivot. We have, therefore, found that a favorable length-diameter ratio can be obtained by displacing the pivot for the breaker supporting plate 5 away from the camshaft axis by an amount making the diameter of this pivot entirely independent from the diameter of the camshaft and its bearing.

The distance between the center of the pivot 9a and the center of the shaft 6a for the cam 6 should be greater than one-half the sum of the diameters of the camshaft and pivot bearing but not so great as to unduly affect the amount of contact separation when the breaker supporting plate 5 is moved through the normal timing range and not greater than the internal radius of the housing 1 and preferably such that at the mid-

portion of advance and retard the follower block is on the line passing through the centers of the pivot 9a and the camshaft center.

One distinct advantage from the standpoint of reduction of cost in employing the small pivot is that only a small bearing would be required even if a ball bearing is employed and the customary large ball bearing surrounding the camshaft, which is expensive and which also had poor length-diameter ratio, would be eliminated.

The present construction is designed primarily for engines operating on a four-stroke cycle and it is, therefore, only necessary to vary the spark timing by an angle measured at the breaker cam-shaft center equal to one-half the crankshaft spark timing range as measured on the engine crankshaft. Since the timing range normally desired does not exceed thirty crankshaft degrees, then the range does not call for an adjustment of over fifteen degrees with reference to the breaker camshaft. Within this small angle the offset of the pivot 9a for the breaker support or plate 5 from the center of the breaker camshaft causes no significant change in the breaker point opening.

On the under side of the breaker support 5 is secured the terminal clip 33 to which is secured one end of the grounding lead 34 which has its opposite end secured to the terminal clip 35 which, in turn, is secured to the upper surface of the supporting plate 2.

The coil springs 21 and 25 normally retain the circuit breaker support 5 and circuit breaker 7 in a retarded position and this is also the case when there is sufficient load on the engine that there will be little if any suction exerted on the diaphragm 24 through the conduit 27 from the carburetor. The result is that due to this retardation of the spark, the engine does not knock during acceleration or idling or operation of the engine under considerable load. However when the operation of the engine is at sufficient speed and without tremendous load on the engine, sufficient suction will be exerted from the carburetor through the conduit 27 on the diaphragm 24 as to move said diaphragm 24 against the action of the spring 25 and to cause the connecting rod 28 to move the breaker support 5 to such position as to advance the spark.

From the foregoing it will be seen that we have provided relatively simple, efficient and economical supporting means for the breaker assembly whereby said assembly may be moved in angular relation to the cam to provide variations of spark timing in relation to engine crank position while eliminating the possibility of any erratic timing and variations in the spark timing and rough running of the motor due to any wobble or loose movement of the breaker assembly.

Having described our invention, we claim:

1. In a device of the character described, a supporting plate having an aperture, a camshaft extending through said aperture, a cam on said shaft and adapted to be rotated thereby, a breaker supporting member pivotally mounted on said supporting plate, a pivot on said plate for said member, said pivot being eccentrically displaced and spaced from said camshaft axis, a breaker contact supporting arm pivotally mounted on said breaker supporting member, a pivot for said breaker contact supporting arm, said pivot being offset from said pivot for said breaker supporting member, and a separate adjustable contact bracket on said breaker supporting member and supporting a contact adjacent the con-

tact on said breaker contact supporting arm and means on said breaker contact supporting arm adapted to engage said cam for effecting operation of said breaker upon rotation of said cam and means for automatically effecting pivotal adjustment of said breaker supporting member and breaker supported thereby as a unit.

2. In a device of the character described, a supporting plate having an aperture, a camshaft extending through said aperture, a cam on said shaft and adapted to be rotated thereby, a breaker supporting member pivotally mounted on said supporting plate, a pivot on said plate for said member, said pivot being eccentrically displaced and spaced from said camshaft axis, a breaker contact supporting arm pivotally mounted on said breaker supporting member, a pivot for said breaker contact supporting arm, said pivot being offset from said pivot for said breaker supporting member, and a separate adjustable contact bracket on said breaker supporting member and supporting a contact adjacent the contact on said breaker contact supporting arm and means on said breaker contact supporting arm adapted to engage said cam for effecting operation of said breaker upon rotation of said cam and means for automatically effecting pivotal adjustment of said breaker supporting member and breaker supported thereby as a unit, the distance between the center of the pivot for the breaker supporting member and the center of said camshaft being greater than half the sum of the diameters of the cam-shaft and pivot bearings.

3. In a device of the character described, a supporting plate having an aperture, a camshaft extending through said aperture, a cam on said shaft and adapted to be rotated thereby, a breaker supporting member pivotally mounted on said supporting plate, a pivot on said plate for said member, said pivot being eccentrically displaced and spaced from said camshaft axis, a breaker contact supporting arm pivotally mounted on said breaker supporting member, a pivot for said breaker contact supporting arm, said pivot being offset from said pivot for said breaker supporting member, and a separate adjustable contact bracket on said breaker supporting member and supporting a contact adjacent the contact on said breaker contact supporting arm and means on said breaker contact supporting arm adapted to engage said cam for effecting operation of said breaker upon rotation of said cam and means for automatically effecting pivotal adjustment of said breaker supporting member and breaker supported thereby as a unit, the distance between the center of the pivot for the breaker supporting member and the center of said camshaft being at least one-half the sum of the diameters of the pivot and cam-shaft and not greater than the internal radius of the housing containing the support.

4. In a device of the character described, a supporting plate having an aperture, a camshaft extending through said aperture, a cam on said shaft and adapted to be rotated thereby, a breaker supporting member pivotally mounted on said supporting plate, a pivot on said plate for said member, said pivot being eccentrically displaced and spaced from said camshaft axis, a breaker contact supporting arm pivotally mounted on said breaker supporting member, a pivot for said breaker contact supporting arm, said pivot being offset from said pivot for said breaker

supporting member, and a separate adjustable contact bracket on said breaker supporting member and supporting a contact adjacent the contact on said breaker contact supporting arm and means on said breaker contact supporting arm adapted to engage said cam for effecting operation of said breaker upon rotation of said cam and means for automatically effecting pivotal adjustment of said breaker supporting member and breaker supported thereby as a unit, said breaker supporting member having a peripheral portion engaging a portion of the periphery of the housing for further steadyng said member.

5. An ignition timing device for an engine including a housing, a rotary cam in said housing, a support carried by said housing, a timing plate pivoted on said support in an axis that is eccentric with respect to the axis of the cam and at a greater distance than the maximum radius of said cam, an ignition timing circuit breaker provided with an element adapted to periodically engage the cam to open the circuit breaker mounted on said timing plate with said element located diametrically opposite to the plate pivotal point with respect to the cam axis.

6. An ignition timing device for an engine including a housing, a rotary cam in said housing, a support carried by said housing, an ignition timing circuit breaker including a cam follower, means pivoted on said support at a point located outside of the maximum radius of the cam for moving said circuit-breaker and cam follower with respect to the cam, a device converting engine suction into movement connected to said means for moving the same, the arrangement being such that the point of application of force produced by said device to said means is diametrically opposite to its pivotal point with respect to the cam axis and the distance of the pivotal point from the cam axis is greater than the distance of the cam engaging face of said follower from the cam axis.

7. An ignition timing device for an engine including a housing, a rotary cam in said housing, a circuit breaker system having a cam follower, a pivoted ignition timing plate for supporting said circuit breaker system, the pivotal point of said timing plate being located outside of the perimeter of the cam, a spring-loaded suction-responsive device connected with said plate for moving the same with respect to said rotary cam for changing the ignition timing imparting movement to the circuit breaker cam follower, the arrangement being such with respect to the cam axis that the movement of the circuit cam

5 follower takes place in an area diametrically opposite to the pivotal point, and the point of connection of the plate with the suction-responsive device is located at a greater distance from the cam axis than the distance of the circuit breaker cam follower therefrom.

8. An ignition timing device for an engine including a housing, a rotary cam in said housing, a support carried by said housing, a timing plate pivoted on said support in an axis that is eccentric with respect to the axis of the cam and at a greater distance than the maximum cam radius of said cam, an ignition timing circuit breaker provided with an element adapted to periodically engage the cam to open the circuit breaker mounted on said timing plate with said element located diametrically opposite to the plate pivotal point with respect to the cam axis.

9. An ignition timing device for an engine including a housing, a rotary cam in said housing, a support carried by said housing, a timing plate pivoted on said support at a point located outside of the perimeter of said rotary cam, a vacuum-actuated device adjacent to the housing, means for connecting said vacuum-actuated device to the plate at a point that is diametrically opposite to the pivotal axis of the plate with respect to the cam axis, and means for initially setting the breaker system cam follower on said timing plate at a point slightly displaced from a plane passing through the point of application of force of the vacuum-actuated device and the plate pivotal point.

10. An ignition timing assembly comprising a relatively stationary supporting member having a central aperture, a movable ignition timing plate, means for mounting said timing plate on said supporting member at a pivotal point spaced from the aperture of the supporting member, a motion-transmitting device connected to the timing plate adjacent its outer periphery, and the said pivotal point and the said point of connection of the motion-transmitting device with said plate being diametrically opposite and located at different radial distances from the center of the supporting member.
